UNITED STATES PATENT OFFICE.

CLARENCE O. SMITH, OF FRYEBURG, MAINE.

RAILROAD-SPIKE.

1,173,882.

Specification of Letters Patent. Patented Feb. 29, 1916.

Application filed July 16, 1915. Serial No. 40,299.

To all whom it may concern:

Be it known that I, CLARENCE O. SMITH, a citizen of the United States, residing at Fryeburg, in the county of Oxford and State 5 of Maine, have invented certain new and useful Improvements in Railroad-Spikes; and I do hereby declare the following to be a full, clear, and exact description of the invention, such as will enable others skilled in 10 the art to which it appertains to make and use the same.

This invention relates to spikes especially designed for securing railway rails to ties, and has for its principal object to provide 15 an improved railroad spike including essentially a main spike element, a locking element movable into a longitudinal bore extending through a portion of the main shank and simple and efficient means for 20 sealing the bore of the spike subsequent to positioning the locking element to exclude moisture.

With this and other objects in view, the invention consists in the novel construction, 25 arrangement and formation of parts as will be hereinafter specifically described, claimed and illustrated in the accompanying drawing, in which:

Figure 1 represents a longitudinal section 30 view through the improved spike. Fig. 2 represents a transverse sectional view on the line 2—2 of Fig. 1, and Fig. 3 represents a side elevation of the locking element removed.

Referring to the drawing in detail, wherein similar reference numerals designate corresponding parts throughout the several views, the numeral 5 indicates the shank of 35 a spike of the usual or any preferred construction having a laterally projecting rail base-engaging head 6 at one end and a cutting edge 7 at the opposite end. From the headed extremity of the spike shank 5 the latter is formed with a longitudinal bore 8 40 terminating at a point adjacent the opposite extremity of the spike shank in a pair of divergent or oppositely curved passages 9, defining deflecting surfaces 10 for deflecting the prongs of the locking element to be hereinafter described. The locking element designated generally by the numeral 11 includes an elongated body or shank portion 45 50 55

annular shoulder 14 and a longitudinal slit 15 extending a distance inwardly of the opposite end defining a pair of prongs or locking tongues 16, the adjacent surfaces of the free ends of which are oppositely beveled, as indicated at 17, to define cutting edges. The bore 8 in the spike shank 5 is preferably 60 rectangular in cross section, as clearly illustrated in Fig. 2, and the body 12 of the locking element is correspondingly shaped so as to lock the same against rotational movement in the shank subsequent to being prop- 65 erly inserted therein.

A gasket 18 formed of lead or other similar soft metal is slidably positioned upon the body 12 of the locking element and is adapted to be engaged by the annular shoulder 14 70 so as to force the gasket into the upper extremity of the bore 8 between the body 12 and the upper extremity of the spike shank 5.

In use, the spike 5 is driven into the tie or other object in the usual manner and the 75 locking element 12 is driven into the bore 8 until the head 13 thereof forces the gasket 18 into the space between the body of the locking element and the wall of the bore 8, as clearly illustrated in Fig. 1 thus effectively 80 sealing the upper extremity of the bore and preventing leakage of moisture therein.

It is further evident that in addition to excluding moisture from the bore of the spike, the gasket 18 in its wedged position 85 provides an efficient and effective means for preventing removal of the locking element and also insures against relative vibratory movement of the locking element and spike incident to the travel of trains over the track. 90

During the longitudinal movement of the locking element, the beveled surfaces 17 of the prongs 16 engage the deflecting surfaces 10 of the curved passages 9 and are curved laterally, as clearly illustrated in Fig. 1, 95 and engage in the fibers of the tie or other object laterally of the spike shank 5, thus reliably locking the latter against removal.

What I claim is:

A spike including a shank having a longitudinal bore extending from one end to a point adjacent the opposite end thereof and terminating in a pair of curved or divergent passages, a locking element having a pair of prongs at one end adapted to engage in said 105 divergent passages, a head at the opposite

end of said locking element, and a malleable metal gasket positioned upon said locking element adapted to be moved into said bore by said head during driving of the locking element to exclude moisture from the bore of the shank and to prevent relative movement of the locking element and shank.

In testimony whereof I affix my signature in presence of two witnesses.

CLARENCE O. SMITH.
